LAMP BASE

Filed April 7, 1930

Caroline A. Burke.
INVENTOR
BY Victor J. Evans
HER ATTORNEY

UNITED STATES PATENT OFFICE

CAROLINE A. BURKE, OF CHICAGO, ILLINOIS

DESIGN FOR A LAMP BASE

Application filed April 7, 1930. Serial No. 35,188. Term of patent 3½ years.

To all whom it may concern:

Be it known that I, CAROLINE A. BURKE, a citizen of the United States, residing at Chicago, in the county of Cook and State of Illinois, have invented a new, original, and ornamental Design for a Lamp Base, of which the following is a specification, reference being had to the accompanying drawing, forming a part thereof.

The figure is a perspective view of the lamp base embodying my design.

I claim:

The ornamental design for a lamp base substantially as shown.

CAROLINE A. BURKE.
